L. C. GREINER

CABINET FOR CALCULATING MACHINES

Filed Sept. 20, 1921

UNITED STATES PATENT OFFICE.

LOUIS C. GREINER, OF EVANSVILLE, INDIANA.

CABINET FOR CALCULATING MACHINES.

Application filed September 20, 1921. Serial No. 501,911.

To all whom it may concern:

Be it known that I, LOUIS C. GREINER, a citizen of the United States, residing at Evansville, in the county of Vanderburg and State of Indiana, have invented certain new and useful Improvements in Cabinets for Calculating Machines, of which the following is a specification, reference being had to the accompanying drawings, forming a part hereof.

My invention relates to cabinets for calculating or other keyboard machines, in which the machine is supported on a platform somewhat below the top of the cabinet and is arranged to be covered up when not in use by a movable cover which, when in closed position is continuous with the top of the cabinet, and is so arranged that it may be swung upward and rearward and dropped into vertical position at the rear of the cabinet, this movement of the movable cover operating to raise the platform carrying the machine into position for convenient operation of the keys of its keyboard. Cabinets embodying this general construction are in general use for typewriting machines and are commonly known as typewriter cabinets. It is the object of my invention to provide a cabinet of this general class which will be simple and strong in construction and will be particularly adapted for use with calculating machines and other keyboard machines which for convenience in use should be brought nearer the operator than is necessary with a typewriting machine and should be inclined forward instead of being on a horizontal plane. A further object of the invention is to provide means by which, when the cabinet is closed, the entrance of dust will be effectively prevented. A further object of the invention is to provide means by which, if desired, the platform carrying the machine may be brought to and held in horizontal position.

With the above described objects, and other objects hereinafter explained, in view my invention consists in the construction and combination of parts hereinafter described.

Referring to the drawings:

Figure 1 is a perspective view of a cabinet embodying my invention shown with the movable cover in open position.

Figure 2 is a cross sectional view showing the supporting platform in raised position.

Figure 3 is a cross sectional view showing the parts in closed position.

Figure 4 is a detail view of the support for the front of the supporting platform, and

Figures 5 and 6 are detail views respectively of the spring for raising the support shown in Figure 4 and the clip for engaging it.

In the drawings 1 indicates the fixed top of the cabinet here shown as supported on front legs 2 and back legs 3, the legs being connected at their upper ends by front board 4, back board 5 and suitable end boards to form a rigid structure. Towards one end this top 1 is cut away to form a space sufficient in size to receive the calculating machine 6. In this space is mounted the movable cover 7, which, when in closed position, is continuous with the top 1, and the supporting platform 8. The movable cover 7 is mounted to swing from horizontal closed position to a vertical position at the rear of the cabinet as shown in Figures 1 and 2. In moving from its horizontal closed position it will uncover the calculating machine and will raise the platform on which the machine is carried and will move it forward so that its front end will project in front of the line of the front of the cabinet, and will also cause the platform to be inclined forward so as to bring its keys into convenient position for use and to enable the paper roll at the back of the machine to be easily seen.

The front board 4 is cut away in line with the space for the movable cover nearly to its lower edge leaving a strip 4' to serve as a support for the front end of the platform 8 when the cabinet is open. The movable cover 7 is provided near its front edge with a depending board 9 which, when the movable cover is in horizontal position fills the space formed by cutting away the front board 4 and rests on the upper edge of the strip 4'.

At the sides of the space in which the machine is received are side boards 10 and 11, the upper edges of which form ledges on which the side edges of the movable cover rest when it is in closed position. These side boards are cut away at their rear ends on curves as shown at 12 these curves serving to guide the rear portion of the movable cover as it is forced rearward into the vertical position in which it is shown in Figures 1 and 2.

Extending rearward from the lower edge of the strip 4' and inclined downward towards the rear is a bottom board 13 extend-

ing to within a short distance of the back board 5 and having an opening 14 formed in it to receive a downwardly extending projection 15 on the under side of the supporting platform 8 near its rear end. At the rear end of this bottom board 13 is hinged, by a spring hinge 16, a downwardly opening door 17 the free edge of which, when it is in closed position, abuts against the lower edge of the back board 5. This door serves to close the space between the rear edge of the bottom board and the back board against entrance of dust or insects when the movable cover is in closed position and is adapted to yield to permit the rear end of the movable cover to pass downward between the rear edge of the bottom board and the back board into the position in which it is shown in Figures 1 and 2.

The supporting platform 8 on which the calculating machine is carried, when the movable cover is in closed position, rests on the bottom board 13 with its projection 15 extending downward through the opening 14, the platform closing this opening against the entrance of dust or insects. When the supporting platform is moved forward its front end rides up on inclines 18 which are provided on the side boards 10 and 11 just inside the strip 4' at the front end of the bottom board onto the upper edge of the strip, and, by the means hereinafter described, is caused to project a substantial distance in front of this strip.

The movement of the platform 8 with the machine carried by it is effected by the movement of the movable cover through levers 21 and links 20. Lever 21 has a fixed pivot 22 on the side board 10 (or 11). It is pivoted at one end to the movable cover just inside the board 9, and its other end is connected by link 20 with the rear end of the platform 8. It is, of course, to be understood that a lever 21 and link 20 is provided at each side of the platform 8. When the cabinet is to be opened, the parts being in the position in which they are shown in Figure 3, the movable cover is raised to the position shown in dotted lines in Figure 2, which swings the levers 21 on their pivots 22 causing the links 20 to begin to push the platform 8 forward. As the movement of the movable cover continues its rear end passes down into the space between the rear edge of the bottom board and the back board and the levers 21 carry the upper ends of links 20 upward and forward lifting the rear end of the platform to the position shown in Figure 2 and forcing the front end of the platform over the edge of the strip 4'. The weight of the movable cover, when it is in its rearmost vertical position, serves to hold the levers 21 in the position shown in Figure 2 and to hold the rear end of the platform in the position shown.

The links 20 being, in the position shown, so nearly in line with the levers 21, any rearward or downward pressure on the platform is without effect to swing the levers to raise the movable cover.

Brackets 26 secured to the side boards 10 and 11 serve to support the levers 21 in rear of the pivots 22. Strips 25 of felt or other thin material secured to the under side of the movable cover at its rear edge serve to close the opening between the rear edge of the movable cover and the portion of the top in rear of the space in which the movable cover is arranged, when the cabinet is closed. A handle 27 on the board 9 serves as a hand hold in moving the cover. The projection 15 in the platform serves as a weight to cause the rear end of the platform to drop readily when the movable cover is drawn forward from the position in which it is shown in Figures 1 and 2 and tends to counter-balance the effect due to the forward inclination of the machine on the platform. The forward curved edge of this projection 15 serves in cooperation with the front end of the opening 14 in the bottom board 13 to guide the rear end of the supporting platform in its upward and downward movement, to limit the forward movement of this supporting platform and to ensure its return to rearward position as it is moved rearward and downward.

If it is desired to have the machine on a horizontal instead of a forwardly inclined base, the devices shown in Figures 4, 5 and 6 may be used. These consist of a U-shaped support 30 having the ends 31 of its legs outwardly extended to form pintles having bearings in blocks 32 secured to the bottom board at its front end just inside the strip 4'. This support, when the cabinet is closed, rests on the bottom board as shown in Figure 3. The platform is provided on its under side with a spring 33 adapted when the platform is moved forward, to engage the support 30 and, as the front end of the platform continues its forward movement, to swing it into vertical position. Clips 34 also carried on the under side of the platform engage the support when it is in its vertical position and hold it in such position, in which position it sustains the front end of the platform at the same level at which its rear end is sustained by the levers 21 and links 20.

Having thus described my invention what I claim is:

In a cabinet for keyboard machines, the combination of a cover arranged to be movable from forward horizontal position to rearward vertical position, a supporting platform for the keyboard machine having a downwardly extending projection on its under side, a fixed bottom board adapted to receive and support the supporting platform

in its rearward position having an opening therein to receive said downwardly extending projection, means operated by the cover for moving the supporting platform bodily forward on the bottom board, raising its rear end and sustaining it in raised position, comprising levers having fixed pivots between their ends and having pivoted connection at one end with the forward end of the cover and links pivoted at one end to the free end of a lever and at the other end pivoted to the rear end of the supporting platform, and means for sustaining the

front end of the supporting platform, the downwardly extending projection, on the supporting platform cooperating with the opening in the bottom board to guide the supporting platform in its forward and rearward movement and pivoted supporting means near the front edge of the bottom board for supporting the front edge of the supporting platform above the front board.

In testimony whereof I hereunto affix my signature.

LOUIS C. GREINER.
